UNITED STATES PATENT OFFICE.

CHARLES ROKAHR, OF EL PASO, TEXAS.

ARCH AND INSTEP SUPPORT FOR BOOTS AND SHOES.

1,204,490.

Specification of Letters Patent. Patented Nov. 14, 1916.

Application filed April 10, 1915. Serial No. 20,398.

To all whom it may concern:

Be it known that I, CHARLES ROKAHR, a citizen of the United States, and a resident of El Paso, in the county of El Paso and 5 State of Texas, have invented certain new and useful Improvements in Arch and Instep Supports for Boots and Shoes, of which the following is a specification, reference being had to the accompanying 10 drawings, forming a part of this specification.

This invention relates to certain new and useful improvements in boots and shoes, the invention comprising an arch and instep 15 support forming a part of the shoe.

The special object of the invention is to provide a boot or shoe with a support adapted to hold the wearer's arch.

Another object of my invention is to provide 20 a shoe provided with a removable arch supporting cushion.

With these and other objects in view the present invention consists in the combination and arrangement of parts as will be 25 hereinafter more fully described and finally pointed out in the appended claims, it being further understood that changes in the specific structure shown and described may be made within the scope of the claims without departing from the spirit of the invention.

In the accompanying drawings forming a part of this specification, and in which like numerals of reference indicate similar 30 parts in the several views: Figure 1 shows a central sectional view of a shoe provided with an arch support embodying my invention. Fig. 2 shows a portion of the sole with parts removed. Fig. 3 shows a detail 35 of the base cushion. Fig. 4 is a section on line 4-4 of Fig. 1, showing one of the flaps folded back and other portions removed. Fig. 5 is a section on line 5-5 of Fig. 1. Figs. 6 and 7 show, respectively, details of 40 the spring members used in my invention.

The object of my present invention is to provide a shoe to meet the needs of those people having defective arches, the shoe including an adjustable means for building up 50 a cushion to properly support the arch of the wearer's foot in a manner described more fully hereinafter.

In the accompanying drawings A design-

nates a shoe provided with an arch support embodying my invention.

1 represents the outer sole, and 2 the inner sole of the shoe.

Embedded between the outer and inner soles is the lower base spring 3, and above this spring are located upon opposite sides 60 the supporting springs 4, 4, a suitable filler 5 being interposed between these superposed springs 4 and 3, as clearly shown in the drawings. These springs are held in position by means of the rivets *a*, these being best shown in Fig. 1. As disclosed the rivets holding the centrally positioned base spring 3 pass through the outer face of the sole, while the rivets holding the remaining springs pass through the inner face 70 of the sole. If desired the upper springs 4 may be laminated. As shown in Fig. 2 a suitable member 6 is also interposed between the springs.

Held upon the shank portion of the sole of 75 the shoe is a base cushion C. This cushion is of such an outline as to snugly fit within a shoe and may be of cork or felt or any other suitable material. This base cushion has its forward and rear ends knife-edged, 80 so that there will be no annoying ridges within the shoe. Secured over the face of this cushion C, as clearly shown in Fig. 5, is a pliable member 10, preferably of kid or other soft leather which has its edges 11 held 85 in place by means of suitable stitching. The opposite edges of this member 10, as shown in Fig. 5, are doubled, the member ending in the overlapping folds or flaps F. These folds F form a pocket within which is removably held an upper cushion L of felt or leather, which has its front and rear ends 90 gradually attenuated, so as not to provide any objectional ridges.

As shown in Fig. 1 the base and upper 95 cushions present a curved upper surface located at a point immediately below the arch of the wearer's foot. In order to further properly sustain the wearer's foot, the shoe is provided with a counter stiffening member 12, clearly shown in Fig. 1, and extending to a point approximately midlength of the cushion. The cushion also extends to a point to the rear of the forward edge of the heel of the shoe, as shown in Fig. 1, as do the 100 superposed springs 3 and 4.

As the upper cushion L can be readily removed or replaced, and as these cushions are made in various thicknesses, the user of the shoe can build up the arch cushions to suit his individual needs.

A cushion embodying my invention is simple and inexpensive in construction, and both durable and efficient in operation, and the inner cushion can be removed or replaced with ease, accuracy and despatch.

Having thus described my said invention what I claim as new and desire to secure by Letters Patent is:

1. The combination with the sole of a shoe, 15 of superposed flat springs embedded within the shank portion of the sole, a base cushion secured to the inner face of the sole above said springs, a pliable member covering said base cushion having its opposite edges secured to said sole and ending in two flaps of 20 a width equal to the width of said sole, and

an upper cushion removably held upon said pliable member, said flaps overlapping said removable cushion to hold the same in place.

2. An arch and instep support comprising a base cushion adapted to be secured to the inner face of the sole of a shoe; a pliable member covering said base cushion having its opposite edges secured to the shoe sole and ending in two flap forming portions 30 of a width equal to the width of the shoe sole, and an upper cushion removably held upon said pliable member said flaps overlapping said removable cushion to hold the same in place.

In testimony whereof I affix my signature. 35
in the presence of two witnesses.

CHARLES ROKAHR.
